UNITED STATES PATENT OFFICE.

LE GRAND PARISH, OF MOUNTAINVIEW, NEW JERSEY, ASSIGNOR TO AMERICAN ARCH COMPANY, OF NEW YORK, N. Y., A CORPORATION OF DELAWARE.

LOCOMOTIVE FIRE BOX.

Application filed July 16, 1919. Serial No. 311,342.

To all whom it may concern:

Be it known that I, LE GRAND PARISH, a citizen of the United States, residing at Mountainview, in the county of Passaic and State of New Jersey, have invented certain new and useful Improvements in Locomotive Fire Boxes, of which the following is a specification.

This invention relates to locomotive fire boxes and is particularly useful in connection with fire boxes of the barrel type.

One of the primary objects of my invention is the provision of an improved arrangement of circulation tubes and arches whereby a refractory combustion chamber may be provided establishing an intense zone of heat through which the products of combustion travel, and whereby efficient combustion is promoted not only because of the intense heat, but also because the gases are thoroughly admixed in their passage through the chamber.

Another object of the invention resides in the provision of an improved arrangement whereby it is possible to increase the size of the circulation tubes, thereby increasing the volume of circulation and consequently making it possible to more rapidly turn over the contents of the boiler, which tends to still further increase the efficiency.

Still another object of the invention resides in an improved arrangement of the circulation tubes which not only makes it possible to attain the foregoing objects, but which also accommodates itself readily to expansion and contraction in the fire box structure.

The foregoing together with such other objects as may hereinafter appear, I obtain by means of a construction which I have illustrated in preferred form in the accompanying drawings, wherein:

Figure 1 is a longitudinal section through a locomotive fire box illustrating the application of my improvements thereto; Figure 2 is an irregular section, enlarged, taken on the line 2—2 of Figure 1; Figure 3 is a section taken on the line 3—3 of Figure 1; and Figure 4 is a section taken on the line 4—4 of Figure 1, on enlarged scale.

Referring now more particularly to Figure 1, it will be seen that the fire box, indicated as a whole by the reference letter A, comprises inside and outside throat

sheets, 7 and 8, respectively; inside and outside side sheets, 9 and 10; inside and outside back sheets, 11 and 12; the crown sheets 13; the cover or roof sheet 14; the flue sheet 15; and the dome course 16. The barrel combustion chamber is indicated by the reference letter B.

In carrying out my invention I provide a plurality of rows of circulation tubes, preferably four tubes to each row, with the tubes of one row in approximately the same vertical plane as the tubes of the other row. The tubes 17 comprising the lower row, extend rearwardly and upwardly from the inside throat sheet 7 to the inside back sheet 11, connecting front and rear water legs. The bend, if any, in these tubes, is preferably located about the middle thereof. The tubes comprising the upper row are of peculiar configuration. At the front end, all of these tubes are expanded in the inside sheet of the barrel, at a point well in advance of the throat, for which purpose each tube is bent at its forward end, as at 18. From the bent portion each tube extends rearwardly and upwardly, in substantial parallelism with the rear portion of the tubes 17, but the tubes of the upper row, instead of being expanded in the inside back sheet 11, are arranged as follows: the central tubes 19 are expanded in the crown sheet 13, and the outer tubes 20 are each respectively expanded in a side sheet.

It will be seen that the foregoing arrangement of the circulation tubes is such that the two rows of tubes diverge toward the front and a maximum spacing therebetween is secured. This enables me to provide a refractory combustion chamber in the fire box, indicated as a whole by the reference letter C, the construction and arrangement of which will now be described.

A transverse refractory wall 23 is supported on the inside sheet of the barrel, intermediate such sheet and the upper row of tubes, the wall being preferably located a short distance to the rear of the bent portions 18 of such tubes. The upper portion of the wall is formed to fit the tubes snugly and the wall, between tubes, projects thereabove, for purposes which will appear. Supported on the upper row of tubes and extending rearwardly of the transverse wall 23 is an arch, indicated as a whole at D, said arch

preferably consisting of three rows of center bricks supported on the tubes, and two rows of wing bricks 24, preferably extending from the point adjacent the transverse wall 5 23 rearwardly, a portion of the length of the arch, said wing bricks being supported from the outer tubes 20 and from the side sheets. The arch is kept from sliding forwardly on the tubes by virtue of the upwardly project- 10 ing portions of the wall 23 intermediate the tubes and the transverse wall is wedged in position between the tubes and the barrel sheet by the arch. Supported on the lower row of tubes are two arches E and F, each of 15 which comprises a row of center bricks 25 supported on an outer pair of the tubes, and a row of wing bricks 26 supported on an outer tube and from the side sheet. The arches E and F are preferably spaced away 20 from the throat sheet 7 by means of the spacer bricks or blocks 27.

It will be seen from the foregoing that the arches constitute a combustion chamber, the front end portions of which are closed at the 25 top, sides and end, the bottom of which has a longitudinal opening or circulation space 28, between the arches E and F, and a transverse opening 29 between said arches and the throat sheet; and the top of which, toward 30 the rear, is open at each side. By this arrangement not only are the gases and products of combustion thoroughly intermingled, but the walls of the combustion chamber act as heat storage and heat reflecting members 35 which radiate and reflect heat from substantially all sides inwardly and which establish an intense zone of heat within the combustion chamber thorough which the major portion of the products of combustion pass 40 and to which they are subjected. More perfect combustion is thus obtained and the efficiency with reference to fuel consumption is greatly increased. Higher temperature values also obtain throughout the fire box. 45 It is further to be noted that the arrangement of the tubes is such that standard forms of brick may be accessibly and removably supported on the tubes.

In addition, it is to be observed that by 50 arranging the tubes of one of the rows to discharge to the side water legs, and the space above the crown sheet, I am enabled to materially increase the diameter of the tubes over what would be practical were all the 55 tubes arranged to discharge in the comparatively restricted rear water leg. I am, therefore, enabled to greatly increase the volumetric capacity of the tubes and thus decrease the time required to turn over the 60 contents of the boiler.

Finally the arrangement of the tubes is such as will not increase the rigidity of the fire box structure which will readily accommodate itself to expansion and contraction. The transverse wall also relieves the upper

row of tubes of a portion of the weight of the arch which is of importance since such tubes are bent at both ends.

I claim:

1. In a barrel type locomotive fire box, the combination of two sets of upwardly and rearwardly extending arch tubes one above the other, said sets converging rearwardly and having their forward ends substantially spaced apart, an arch carried on the upper set and an arch carried on the lower set, the lower arch having a gas circulation space extending longitudinally thereof and one extending transversely at the forward portion thereof, and said arches forming a combustion chamber in the forward portion of the fire box. 75

2. In a barrel type locomotive fire box, the combination of two sets of upwardly and rearwardly extending arch tubes one above the other, said sets converging rearwardly and having their forward ends substantially spaced apart, an arch carried on the upper set and an arch carried on the lower set, and a cross wall supported on the barrel adjacent the forward edge of the upper arch, the lower arch having gas circulation spaces therethrough, and said arches together with said wall forming a combustion chamber in the forward portion of the fire box. 85

3. In a locomotive fire box of the barrel combustion chamber type having front and rear water legs, a water space around the barrel and one above the fire box, the combination of a set of arch tubes extending from the front water leg to the rear water leg and a set of tubes above the first set extending from the water space around the barrel to the space above the fire box, said sets converging rearwardly and having their forward ends substantially spaced apart, an arch carried on the upper set of tubes and an arch carried on the lower set of tubes having gas circulation spaces therethrough, said arches forming a combustion chamber in the forward portion of the fire box. 100

4. In a locomotive fire box of the barrel combustion chamber type having front, rear and side water legs, a water space around the barrel and one above the fire box, the combination of a set of arch tubes extending from the front water leg to the rear water leg, and a set of tubes above the first set some of which extend from the space around the barrel to the side water legs and the balance to the space above the fire box, said sets converging rearwardly and having their forward ends substantially spaced apart, an arch carried on the upper set of tubes and an arch on the lower set having gas circulation spaces therethrough, said arches forming a combustion chamber in the forward portion of the fire box. 115

5. In a barrel type locomotive fire box hav- 120

- ing a front water leg and a water space around the barrel, the combination of a set of arch tubes extending upwardly and rearwardly from the front water leg, another set thereabove extending upwardly and rearwardly from the water space around the barrel, said sets converging rearwardly and having their forward ends substantially spaced apart, an arch carried on the upper set and an arch carried on the lower set, the lower arch having gas circulation spaces therethrough, and said arches forming a combustion chamber in the forward portion of the fire box.
6. In a locomotive fire box of the barrel combustion chamber type having a front water leg, a water space around the barrel, and water spaces at the rear of the box, the combination of a set of arch tubes extending from the front water leg to a rear water space and a set of tubes above the first set extending from the barrel water space to a rear water space, said sets converging rearwardly and having their forward ends substantially spaced apart, an arch carried on the upper set of tubes, and an arch carried on the lower set of tubes having gas circulation spaces therethrough, said arches forming a combustion chamber in the forward portion of the fire box.
7. In a barrel type locomotive fire box, the combination of two sets of upwardly and rearwardly extending arch tubes one above the other, said sets converging rearwardly and having their forward ends substantially spaced apart, an arch carried on the upper set, an arch carried on the lower set, and a cross wall adjacent the forward edge of the upper arch, the lower arch having gas circulation spaces therethrough, and said arches together with said wall forming a combustion chamber in the forward portion of the fire box.

In testimony whereof, I have hereunto signed my name.

LE GRAND PARISH.
